UNITED STATES PATENT OFFICE.

JEREMIAH JOHN SHEEHY, OF NEW YORK, N. Y., ASSIGNOR TO UNDERWOOD TYPE-WRITER COMPANY, OF NEW YORK, N. Y., A CORPORATION OF DELAWARE.

TYPEWRITING-MACHINE.

1,380,931.

Specification of Letters Patent. Patented June 7, 1921.

Application filed April 27, 1920. Serial No. 376,905.

To all whom it may concern:

Be it known that I, JEREMIAH JOHN SHEEHY, a citizen of the United States, residing in New York, in the county of New 5 York and State of New York, have invented certain new and useful Improvements in Typewriting-Machines, of which the following is a specification.

This invention relates to typewriting machines, and is disclosed as applied to an Underwood standard typewriting machine of the fan-fold or so-called continuous billing type, one form of which is shown in the patent to Wernery and Smith, No. 1,132,055, 15 dated March 16, 1915.

It has been desired to type simultaneously not only the usual flexible work-sheets, but also a card. To insure that cards thus made out shall be of the greatest utility in book-20 keeping systems, it is desired that they be made out with their typed-lines falling exactly in the proper places, to facilitate the reading of the cards when subsequently turning them over in card-record cases. The 25 insertion of cards has, however, in the past, proved troublesome in this class of machines, because the card was usually a great deal stiffer than the work-sheets, with the result that it bent differently, and so was not readily 30 adjusted to the usual gages. In many forms of machines, hitherto in use, the addition of a separate gage for a card involved adding so much to the complexity of the mechanism, or so much to the number of 35 movements performed by the typist in inserting the work-sheets, that the use of cards in connection with billing machines has hitherto been very restricted.

According to the present invention, the 40 typewriting machine may be provided with a special gage adapted to hold the card in such a position that, when the other work-sheets are properly alined or gaged, and the mechanism is actuated to hold the work-sheets in their alined positions, the card, 45 already inserted, and gaged by a card-gage, is simultaneously grasped at the position to which it has been set by the typist.

In machines of the Wernery and Smith 50 type, referred to above, the platen is displaceable in the typewriter-carriage, so that work-sheets or work-webs may be drawn forward from the rear, substantially straight, beneath the platen, and gaged against a lead-55 ing-edge gage. Such machines are also usu-

ally provided with a knife a little above the printing line, with the result that, after the work-sheets are gaged in the manner described, they are seized by the platen at its return to typing position, and, when thus seized, are usually in position to be severed by being drawn against the knife. Such machines are usually provided with a rearward extension of the typewriter-carriage, upon which runs a carbon-paper-carrier, and, according to the present invention, this extension may include a card-gage, which normally may lie flat upon said extension, but which is adapted to be cammed out of the way by the advance of the carbon-paper-carrier. The new card, which is inserted at this time and gaged, will not extend as far forward as the knife, but will be grasped by the platen at the swinging down of the platen from its displaced position, with the result that the new card is held at typing 75 position, but not within reach of the knife; while the old card is above the knife, having been drawn forward with the webs at the gaging operation, and may be grasped with 80 the leading edges of the work-sheets or webs when they are swung against the knife to sever them. Since the card is usually shorter than the detached form, and is never longer, it is above the knife and so is 85 uninjured at the severing operation.

The card-gage may be adjustable to suit various sizes of cards, and, since it lies flat at the time the new card is being adjusted, there is no likelihood that the card will be 90 moved from its accurately-adjusted position in the manipulation of the mechanism, preliminary to beginning the next typing.

Other features and advantages will hereinafter appear.

In the accompanying drawings,—

Figure 1 is a fragmentary, perspective view of an Underwood typewriting machine carriage of the character described, and showing the present invention as applied 100 thereto.

Fig. 2 is a sectional side view of the same, showing the platen in its displaced position, with the new card inserted, and the old card not yet withdrawn.

Fig. 3 is a view similar to Fig. 2, but showing the platen swung back, ready for typing, after the typed forms have been detached.

In the Underwood standard continuous 110

billing machine, webs 1, 2 and 3, which are usually fan-folded, are drawn from the rear, over the rear cross-bar 4 of an extension 5 of the typewriter-carriage 6. The webs are 5 threaded between carbon-clip-bars 7 on a carbon-paper-carriage 8, and thence carried forwardly over a rear paper-table 9, and up in front of the platen 10. Usually, the webs 1, 2 and 3, in the normal position of the 10 platen, are held against the platen by rear feed-rolls 11 and front feed-rolls 12, so that the action of the line-space-lever (not shown) feeds the webs forwardly in rotating the platen 10. The webs usually extend upward 15 in front of the platen, after being typed, so that they lie upon a front paper-table 13, which forms part of a swing-frame 14, in the ends of which the platen is journaled. Carbon-sheets 15 and 16 extend between the webs 1 and 2 and 2 and 3, so that 20 matter typed upon the outer web 3 is reproduced upon the inner webs 1 and 2.

Usually, there are forms printed upon the webs, and, when a form has been completely 25 typed, the swing-frame 14 is released, by pressing rearwardly a finger-piece 17, and is then swung forward to the Fig. 1 or Fig. 2 position, so that the webs may be drawn forward, substantially straight, beneath the 30 platen, which has been swung up, and may be gaged against the usual adjustable leading-edge gage 18. After the webs have been thus gaged, the platen is usually swung back against the feed-rolls 11 and 12, and the 35 gaged forms are detached by drawing them against a knife 19, which usually stands a little above the printing line. Frequently, the knife is so positioned that the severing of the webs by it leaves the first line to be 40 typed upon the next form exactly at the printing line, the knife covering only a printed heading. The clip-bars 7 are usually detachably mounted upon the carbon-paper-carriage 8, and said carriage usually runs 45 upon side rails 20 and 21, forming part of the extension 5.

According to the form of the present invention, herein illustrated, there may be provided an extra carbon-sheet 22 upon an 50 additional one of the clip-bars 7, so that the matter typed upon the webs 1, 2 and 3 may be reproduced upon a card 23, lying adjacent the platen. The card is adapted to be inserted, in this type of machine, when the 55 platen is displaced and the webs have been advanced to the leading-edge gage 18. Usually, the typist will gage the webs 1, 2 and 3 against the gage 18, then push rearwardly the carbon-paper-carriage 8, by its handle 60 24, to reposition the carbon-sheets relatively to the webs, and then insert the card 23, gaging it against a gage 25, which is provided, according to the present disclosure, upon the typewriter-carriage 6, and is preferably adapted to be swingable above the 65

extension 5. After the card is thus positioned, the platen is returned to its normal typing position, as described above, the card being bent down by the returning of the platen, so that it lies in the Fig. 3 position, 70 next the platen. The card usually bends up behind the leading-edge gage 18 because of its stiffness.

Since the gage 25 is preferably in the form of an L-bar, having a bottom 26, upon which the card is adapted to rest when being positioned, and is preferably horizontal when positioned, means are herein shown for enabling the gage 25 to be swung upwardly out of the way of the carbon-paper-carriage 8. For this purpose, it is swingable, as above described, being pivoted on a shoudered screw 27, which is threaded into an upstanding fixed arm 28 upon a cross-bar 29, commonly found in the machines built 85 according to said patent, and over which the webs usually bend in descending to the paper-table 9.

To enable the gage 25 to be adjusted, it is provided with a forwardly-extending arm 90 30, which may extend downwardly to form a side gage-plate 31 for the webs 1, 2 and 3, and may be adjustably connected to the screw 27. The adjustment, herein shown, is provided by a thumb-screw 32, threaded 95 onto a post 32^a, which passes through a slot 33 on an arm 34, which forms the pivotal support of the gage 25 upon the screw 27. To normally support the gage 25 in its horizontal position, the plate 31 is provided 100 with a small bracket-lug 35, which is adapted to rest upon the top of the rail 21. To enable the gage 25 to be swung upwardly, at the advance of the carbon-paper-carriage 8, the lower edge of the plate 31 is formed as 105 a cam 36, which is adapted to be struck by the advancing edge 37 of the carbon-paper-carriage 8, and to be lifted thereby, and to be carried up farther, so that the gage 25 is 110 swung to the Fig. 3 dot-and-dash-position. The fact that the gage is swung to this position, in no wise interferes with the accuracy of the gaging of the card 23 thereby, since, by the time the gage has been lifted, the card 23 has been seized between the 115 platen 10 and one or both of the feed-rolls 11, 12.

As will be seen from Fig. 2, the card 23 is readily insertible from the rear by the typist, whose right hand at this time is 120 usually gaging the webs against the leading-edge gage 18, while the swing-frame 14 is supported on the usual bolsters 40, thus allowing the left hand of the typist to be free to insert the card 23 behind the platen, 125 and, if needed, to push it slightly forward to the position shown in Fig. 2—the position, however, differing with the relationship of the card to the typed forms. In 130 the form of the invention herein illustrated,

the gage 25 only extends part way across the extension 5, thus giving the typist more freedom in adjusting the card 23 against the gage. The gage, however, preferably extends rather more than half way across the extension, thus furnishing the typist a long gage, against which the bottom edge of the card may be adjusted. To enable the gage-plate 31 to be adjusted widthwise of the machine, the arm 34, instead of being unitary, as implied above, may be adjustable widthwise, and, for this purpose, it is interrupted at 41, and there comprises a lug 42, into which is threaded a thumb-screw 43, which passes through a slot 44 in an opposing lug 45, the slot being of sufficient length to enable the desired adjustment of the gage 31 in the direction described. It will be observed that the gage-plate 31 lies inside of the rail 21, and may be attached to practically any of the standard types of continuous billing machines, without alteration of the carbon-carriage, since the cam 36 may strike any place on the front of the carbon-paper-carriage.

After the card 23 has been inserted and brought to the Fig. 3 position, typing proceeds. When the webs 1, 2 and 3 are drawn against the leading-edge gage 18 in the manner described above, the card is usually drawn with them, and then held with them during the insertion of the new card 23, and until the platen is thrown back to its Fig. 3 position for typing the new card. The old card may then be withdrawn by the typist when severing the webs 1, 2, 3.

If it is desired to have the card extend farther to the right than the webs 1, 2, 3, the gage 25 may be so adjusted that its side-gaging plate 31 is at the desired position for gaging the card, while the webs are gaged by the usual side-gages 46, adjustably mounted upon the carbon-paper-carriage 8. The webs may be further guided by side-gages used on certain types of billing machines of this general character, one of said gages being illustrated at 47 upon the rear cross-bar 4. To enable the gage 25 to be used with a narrow card and narrow webs, the bracket 35 may be made of such a length that it never clears and falls down inside the rail 21.

Variations may be resorted to within the scope of the invention, and portions of the improvements may be used without others.

Having thus described my invention I claim:

1. In a typewriting machine, the combination with a carriage and a revoluble platen therein, of a carbon-paper holder behind the platen adapted to move with the advancing carbons; a gage behind the platen adapted to hold a card, and connections whereby the advancing holder moves the gage out of its path.
2. In a typewriting machine, the combination with a carriage and a revoluble platen therein, of a carbon-paper holder reciprocable behind the platen in a substantially horizontal line, a gage behind the platen adapted to hold a card substantially in said line, and means effective at the advance of the carbon-paper holder, to move the gage out of said line to permit the advance of the holder.
3. In a typewriting machine, the combination with a carriage and a revoluble platen therein, of an extension of the carriage behind the platen, a carbon-paper holder reciprocable on said extension, a gage behind the platen adapted to hold a card substantially in the path of said holder, a pivot on which the gage is adapted to swing out of said path, and a cam by which the holder swings the gage clear of its path.
4. In a typewriting machine, the combination with a carriage and a revoluble platen therein, of a frame for the platen in which it is displaceable on the carriage to permit work-webs to be drawn substantially straight beneath it, an extension of said carriage behind the platen, a carbon-paper holder adapted to run on said extension, a gage on said extension adapted to position a work-sheet by its bottom edge, so that it extends beneath the platen in its displaced position with the work-webs, and means whereby the advance of the holder carries the gage out of its path.
5. In a typewriting machine, the combination with a carriage and a revoluble platen therein, of a frame for the platen in which it is displaceable on the carriage to permit work-webs to be drawn substantially straight beneath it, an extension of said carriage behind the platen, a carbon-paper holder adapted to run on said extension, a gage pivoted on the carriage, and adjustable to position a work-sheet by its bottom edge, so that the leading edge extends with the work-webs beneath the platen in its displaced position, and a cam adapted to swing the gage clear of the holder at the advance of the latter.
6. In a typewriting machine, the combination with a carriage and a revoluble platen therein, of a frame for the platen in which it is displaceable on the carriage to permit work-webs to be drawn substantially straight beneath it, an extension of said carriage behind the platen, a carbon-paper holder adapted to run on said extension, a bottom-end-gage on said extension including a side gage adjustable therewith; said gage adjustable along the travel of the webs and across them, and adapted to position a work-sheet by its bottom and side edges, so that the leading edge extends with the work-webs beneath the platen in its displaced position, and a device adapted to move the gage out

of the path of the holder at the advance of the latter.

7. In a typewriting machine, the combination with a carriage and a revoluble platen therein, of a frame for the platen in which it is displaceable on the carriage to permit work-webs to be drawn substantially straight beneath it, an extension of said carriage behind the platen, a carbon-paper holder adapted to run on said extension, a bottom-end-gage on said extension including a side gage adjustable therewith, said gage adjustable along the travel of the webs and across them, and adapted to position a work-sheet by its bottom and side edges, so that the leading edge extends with the work-webs beneath the platen in its displaced position, a pivot on which the gage is adapted to swing, and a cam on the gage adapted to be struck by the advancing carbon-paper holder, to lift the gage out of the path of the holder.

8. In a typewriting machine, the combination with a carriage and a revoluble platen therein, of a frame for the platen in which it is displaceable on the carriage to permit work-webs to be drawn substantially straight beneath it, an extension of said carriage behind the platen, a carbon-paper holder adapted to run on said extension, a bottom-edge-gage pivoted upon the carriage, an adjustable member between the gage and its pivot, to enable the gage to be adjusted lengthwise of the webs, a side gage mounted on said member and adjustable sidewise with it, and means for moving the gage clear of the holder at the advance of the latter.

9. In a typewriting machine, the combination with a carriage and a revoluble platen therein, of a frame for the platen in which it is displaceable on the carriage to permit work-webs to be drawn substantially straight beneath it, an extension of said carriage behind the platen, rails at the margins of said extension, a carbon-paper holder adapted to run upon said rails, a gage pivoted to lie between said rails to gage the bottom edge of a work-sheet, so that its leading edge lies with the work-webs beneath the platen, and means for lifting the gage out of the path of the holder by the advance of the latter.

10. In a typewriting machine, the combination with a carriage and a revoluble platen therein, of a frame for the platen in which it is displaceable on the carriage to permit work-webs to be drawn substantially straight beneath it, an extension of said carriage behind the platen, rails at the margins of said extension, a carbon-paper holder adapted to run upon said rails, a gage adapted to lie between said rails to gage the bottom edge of a work-sheet, so that its leading edge lies with the work-webs beneath the platen, a pivot for said gage, and

an adjustable member connecting the gage to its pivot.

11. In a typewriting machine, the combination with a carriage and a revoluble platen therein, of a frame for the platen in which it is displaceable on the carriage to permit work-webs to be drawn substantially straight beneath it, an extension of said carriage behind the platen, rails at the margins of said extension, a carbon-paper holder adapted to run upon said rails, a gage adapted to lie between said rails to gage the bottom edge of a work-sheet, so that its leading edge lies with the work-webs beneath the platen, a member forming a side gage and adjustably supporting said first gage, a pivot on the carriage, and means for sidewise adjustably supporting the side gage on the pivot.

12. In a typewriting machine, the combination with a carriage and a revoluble platen therein, of an extension of the carriage behind the platen, a carbon-paper holder reciprocable on the extension, a frame in which the platen is mounted in said carriage to enable it to be displaced therein to enable work-webs to be drawn forward substantially straight beneath it, and a bottom-edge-gage for a work-sheet lying above the webs, and adapted to hold the leading edge beneath the platen with the webs.

13. In a typewriting machine, the combination with a carriage and a revoluble platen therein, of an extension of the carriage behind the platen, a carbon-paper-carriage reciprocable on the extension, a gage adjustable on said carbon-paper-carriage, to gage the sides of webs, a frame in which the platen is mounted in said carriage, to enable it to be displaced therein, a bottom-edge-gage for a work-sheet lying above the webs, a side-gage connected to said bottom-gage, and means for adjusting the last-named gage independently of the carbon-paper carriage.

14. In a typewriting machine, the combination with a carriage and a revoluble platen therein, of an extension of the carriage behind the platen, a carbon-paper-carriage reciprocable on the extension, a frame in which the platen is mounted in said carriage, to enable it to be displaced therein, to enable work-webs to be drawn forwardly, substantially straight beneath it, a leading-edge-gage for the webs upon said frame, a bottom-edge-gage for a work-sheet lying above the webs, but adapted to gage a work-sheet lying immediately above them, and means for moving said bottom-edge-gage out of the path of the carbon-paper-carriage.

15. In a typewriting machine, the combination with a carriage and a revoluble platen therein, of an extension of the carriage behind the platen, a carbon-paper-carriage reciprocable on the extension, a frame in which the platen is mounted in said car-

- riage, to enable it to be displaced therein, to enable work-webs to be drawn forwardly, substantially straight beneath it, an adjustable leading-edge-gage for the webs upon
- 5 said frame, a separately-adjustable bottom-edge-gage for a work-sheet lying above the webs, but adapted to gage a work-sheet lying immediately above them, and means for moving said bottom-edge-gage out of the
- 10 path of the carbon-paper-carriage.
16. In a typewriting machine, the combination with a carriage and a revoluble platen therein, of an extension of the carriage behind the platen, a carbon-paper-carriage reciprocal on the extension, and through which webs are adapted to be threaded, a pivot on the carriage, an arm swingable on said pivot, an extension adjustable on said arm, and a bottom-edge-gage adjustable on said last-named extension.
- 15 18. In a typewriting machine, the combination with a carriage and a revoluble platen therein, of an extension of the carriage behind the platen, a carbon-paper-carriage reciprocal on the extension, a frame in which the platen is mounted in said carriage, to enable it to be displaced therein, to enable work-webs to be drawn forwardly, substantially straight beneath it, a leading-
- 20 edge-gage for the webs upon said frame, a bottom-edge-gage for a work-sheet lying above the webs, but adapted to gage a work-sheet lying immediately above them, means for moving said bottom-edge-gage out of the
- 25 path of the carbon-paper-carriage, a side-gage for the webs, and a separate, adjustable side-gage for the work-sheet gaged by the bottom-gage.
17. In a typewriting machine, the combination with a carriage and a revoluble platen
- 30 therein, of an extension of the carriage behind the platen, a carbon-paper-holder reciprocal on the extension, a frame in which the platen is mounted in said carriage, to
- 35 enable it to be displaced therein, to enable work-webs to be drawn forward, substantially straight beneath it, a bottom-edge-gage for a work-sheet lying above the webs, and adapted to hold the leading edge be-
- neath the platen with the webs, and a member connected with said bottom-edge-gage for supporting the bottom-edge of the work-sheet against the gage.
19. In a typewriting machine, the combination with a carriage and a revoluble platen
- 40 therein, of an extension of the carriage behind the platen, a carbon-paper-carriage reciprocal on the extension, and through which webs are adapted to be threaded, a pivot on the carriage, an arm swingable on said pivot, an extension adjustable on said arm, and a combined bottom and side-gage adjustable on said last-named extension.
20. In a typewriting machine, the combination with a carriage and a revoluble platen
- 45 therein, of an extension of the carriage behind the platen, a carbon-paper-carriage reciprocal on the extension, and through which webs are adapted to be threaded, a pivot on the carriage, an arm swingable on said pivot, an extension adjustable on said arm, and a bottom-edge-gage adjustable on said last-named extension, and an adjustable leading-edge-gage for the webs.

JEREMIAH JOHN SHEEHY.
